MEANS FOR REGISTERING NEGATIVES FOR
PHOTOGRAPHIC PRINTING MACHINES

William C. Huebner, Chicago, Ill.

Application August 4, 1928. Serial No. 297,511

4 Claims. (Cl. 33—184.5)

This invention relates to improvements in means for registering negatives for photographic printing machines.

In the art of photographically preparing press plates for printing, it is customary to use a photographic printing machine or photo-composer which consists, essentially, of a main frame; holding means for the press plate; holding means for the negative; and means for effecting 10 relative shifts, in parallel planes, between the negative and plate in two directions at right angles to each other, whereby the negative can be positioned over any desired point of the press plate and thereupon brought into intimate 15 contact and exposure made. Generally, in such machines, the negative is carried by a negative frame mounted on a negative holder, the latter in turn being mounted in a definite position on a sub-carriage which is adjustable on a main 20 carriage in one direction, the main carriage in turn being adjustable on the main frame and with reference to the press plate, in a direction at right angles thereto. With such constructions, the positions of the negative holder with 25 reference to the press plate can be definitely ascertained at any time by suitable scales indicating the two travel lines of the machine, that is, the line of travel of the main carriage on the frame and the line of travel at right 30 angles thereto of the sub-carriage on the main carriage. To know accurately the position and location of the negative (or more accurately, the image on the negative to be reproduced on the press plate) extreme accuracy of registration 35 of the negative on its immediate negative holding frame is necessary, and to obtain this it has been the usual practice to register the negative in its holding frame by means of a separate machine known as a "registering machine or device" such as shown in my prior Patent 1,291,897, granted January 21, 1919.

Heretofore, the most common form of negative used has been glass, which negatives are, from a practical standpoint, free from any objection on account of expansion and contraction and can easily be bodily shifted relative to their immediate holding frames and clamped in adjusted position. There are, however, practical limitations to the size of glass negatives 45 which can be used and, hence, to the separate registering devices heretofore employed therewith. In certain classes of work, particularly large posters, it is not always feasible to use glass negatives and consequently resort is now 50 frequently being had to flexible films made of

paper or other similar material. Flexible or paper films are frequently of relatively large size requiring correspondingly large frames for holding the same and, to effect register of the images on such flexible films is extremely difficult in any of the usual types of registering machines, because of the necessity of localized stretching and conditioning of different portions of the film, as more fully explained in my application, Serial No. 295,683, filed July 27, 1928, 60 now Patent 1,870,008, granted August 2, 1932.

One object of my invention, therefore, is to provide simple and efficient means for effecting register of a negative after it has been secured in fixed operative position with respect to its 70 immediate holding frame so that the negative may be first secured in place and the register effected thereafter.

Another object of my invention is to provide means for effecting registration of a flexible film 75 after the latter has been secured taut in its holding frame.

Another object of my invention is to provide means for obtaining register of negatives by adjustment of the film or negative holding frame 80 relative to the negative main holder, which latter is adapted to be directly attached to the photographic printing machine.

Another object of my invention is to provide a registering device wherein the negative holder, 85 which is adapted to be secured to the machine proper, is utilized as part of the means for effecting registration between it and a negative or film secured to a film holding frame.

Other objects of the invention will more clearly appear from the description and claims hereinafter following.

In the drawings forming a part of this specification, Figure 1 is a plan view of a negative main holder, with a flexible film frame in place 90 thereon and means for obtaining register of the film with respect to the holder. Figure 2 is an enlarged vertical detail section corresponding approximately to the line 2—2 of Figure 1, illustrating some of the structural features of 100 the holder frame and means for obtaining register. Figure 3 is a vertical sectional view corresponding to the line 3—3 of Figure 2. Figure 4 is a top plan view, upon an enlarged scale, of the parts shown in Figure 3. Figure 5 is a detail perspective of the two register bars at the points of intersection. Figure 6 is a detail view of the structure at the corner of the apparatus, showing more particularly the method of securing the film frame after it has been adjusted. 110

Figure 7 is a view similar to Figure 3 illustrating a modification. Figure 8 is a top plan view of the construction illustrated in Figure 7. And Figure 9 is a detail sectional view of a modified 5 form of register bar.

Referring first to the construction illustrated in Figures 1 to 6 inclusive, the main negative holder is indicated generally by the reference character A; the film frame by the reference 10 character B; an auxiliary supporting frame by the reference C; and the register bars by the reference characters D and E.

The main holder A is preferably of rectangular form having a central opening as indicated at 15 10 and comprised of a main flat plate 11 around the periphery of which is provided a strip of sponge rubber 12 for effecting an air seal with an opposed press plate. The rubber strip 12 is secured to the main plate 11 in any suitable 20 manner, as for instance by the channel formation comprised of the lower plate 13 and side gripping plates 14-14. Suitable means are provided for attaching the holder A to the usual sub-carriage of the photographic printing machine proper, in a definite predetermined position 25 and location with respect to said sub-carriage so that the center of the holder A may always be determined by proper reading of the scales corresponding to the two travel lines of 30 the machine, as hereinbefore explained. For this purpose, I preferably provide the holder A with two dowel holes 15-15 on one narrow edge thereof and with two other dowel holes 16-16 on a long side thereof, which dowel holes are 35 adapted to cooperate with an accurately fitting, corresponding pair of dowels on the sub-carriage. By providing two sets of dowel holes, as above described, the angular position of the holder A may be turned through 90°, so as to 40 position the image either head up, head down, head right, or head left, as may be required by any particular job.

The auxiliary frame C is also of rectangular outline, having a centrally disposed opening 17 coinciding with the opening 10 of the main 45 holder A. Said frame C preferably consists of a relatively thick metal plate and is supported in fixed position with reference to the holder A by any suitable means, such as the dowels 18, 50 carried by the holder A and which enter corresponding dowel hole bushings 19-19 of the frame C. To effect an air seal between the auxiliary frame C and the holder A, the frame is preferably provided with a flexible flap 20 55 of rubber or other suitable material extending entirely around the opening 17 and backed throughout by a sponge rubber strip 21. The flap and rubber strip are secured to the frame C preferably by narrow plates 22.

60 The film frame B is also of rectangular form, having a central opening 23 to permit passage of the light rays through the film or negative during exposure. Said film frame may be of any suitable construction but preferably is comprised of upper and lower plates 24-25 and a 65 vertical inner plate 26, with suitable blocks interposed therebetween and leaving chambers or spaces within which are slidably received a plurality of stretching blocks 27. Each of the 70 blocks 27 preferably has its outer end tapered as indicated at 28 and cooperable therewith is a clamping jaw 29 for the flexible film sheet 30. Each jaw 29 is adapted to be tightened against its corresponding block 27 by a pair of suitable 75 adjusting screws 31-31. The stretching of the

film is effected by moving the combined clamping jaw and block 29-27 outwardly, which is accomplished by means of an adjusting screw 32. Preferably there will be employed a backing sheet of celluloid or the like 33 for the flexible film, said sheet 33 bridging the opening of the film frame B and secured around its edges to the frame B by suitable means, such as the plate 30.

To insure an air seal between the film frame B and the auxiliary frame C, the latter may have mounted on the upper surface thereof a thin rubber strip 35 and another rubber strip 36 may be interposed between the film and the top surface of the film frame B. The parts so far described are or may be, the same or substantially the same, as described and claimed in my said Patent 1,870,008.

In carrying out my invention, the flexible film 30 will first be secured in a taut condition to the film frame B, this being accomplished while the frame B is disassembled from the rest of the structure and, preferably, also, the film will have been treated so as to render the same impervious to moisture and temperature changes.

With the film secured to the film frame and the latter then assembled with the main holder A, registration of the negative or film is effected in the following manner.

Detachably secured to the main holder A are 105 two register or line-up bars D and E. Adjacent the center of each side of the holder A and on the inner side of the rubber sealing strip 12, the holder A has secured thereto a narrow steel block 37 so positioned as to be clear of the adjusting screws 31 and 32. Each said block 37, as best shown in Figure 3, is adjustably secured to the holder A in a direction lengthwise of the corresponding side of the holder, by any suitable means, such as the screws 38-38 which extend down through elongated openings 39-39 in the block, the heads of said screws 38 being countersunk below the top surface of the block, as clearly shown in said figure. Each block 37 is preferably provided with a dowel hole 40 in its 120 upper face into which is adapted to be entered a corresponding dowel pin 41 integral or rigid with the corresponding bar D or E. The bars D and E are preferably of the cross section indicated in Figure 3 and are formed along one 125 edge thereof with a bevel as indicated at 42 so as to obtain a very sharp knife edge. Said edge is also preferably notched at relatively close intervals, as indicated at 43-43, in Figure 5, 130 for the purpose hereinafter described.

The bars D and E are so positioned that the same substantially rest upon the film 30 when the latter is in place so that the knife edges 42 of the bars extend in very close proximity to the film to facilitate register as about to be described.

The blocks 37 may be adjustable as above described, so as to provide for an extremely accurate adjustment of the ends of the bars D and E and when the proper adjustment of the blocks 37 has once been obtained, they are permanently locked to the holder A. The blocks 37 are so adjusted that the knife edges of the bars D and E will extend exactly at right angles 145 to each other and in exact parallelism with the two travel lines of the machine proper, which also are at right angles. Further, the said knife edges will coincide exactly with the median lines of the holder A so that said two knife edges, 150

projected, intersect at the exact center of the holder.

In this art, it is customary to provide each negative or film with register marks which are almost universally in the form of little crosses, as indicated at 44—44, said crosses being located outside of the area of the actual image to be reproduced and, further, coinciding with two lines at right angles to each other, which intersect at the center of the actual image, as nearly as possible. The said register or cross marks will be in the same position on all the negatives or films of a series, where a series is employed, as for instance, in color work.

With the arrangements which I have shown and with the bars D and E in place, the film frame B is then shifted or adjusted preferably by hand until the vertical lines of the two upper and lower cross marks 44 coincide exactly with the knife edge of the vertical bar D. Similarly, the horizontal lines forming parts of the two horizontally disposed cross marks 44 are made to coincide exactly with the knife edge of the horizontal bar E. The lines forming the crosses or register marks 44 are usually very fine and so accurate is the registration required that I have provided the notches 43 to insure exact registration and to eliminate error which may occur, due to the lines of the marks being partially obscured beneath the knife edges of the register bars. By employing the notches 43 and spacing them at close intervals, a part of each register mark will be exposed within the notch, so that the operator may assure himself that the line is exactly centrally disposed beneath the knife edge at each point of registration.

When the film frame B, with its film thereon, is registered in the manner just described, the film frame B is then locked with reference to the holder A by suitable means, such as those most clearly illustrated in Figure 6. Preferably the frame B is provided at each corner thereof with an angular block 45 having an arcuate slot 46 therein through which is extended a securing screw 47 threaded to the main plate 11 of the holder A. A washer 48 may be interposed between the head of the screw and the block 45, it being understood that the head of the screw will be disposed below the level of the film so as to avoid any projection thereabove and thus prevent scratching or injury of the press plate when an exposure is made. Adjusting screws 80—80 are also provided, which engage in threaded portions of the frame 45, the square or hexagonal ends of the screws being adapted to abut against the holder A to lock the frame 45 against displacement after the image has been registered.

Referring to Figure 5, the bars D and E are shown as oppositely recessed or notched as indicated at 49 and 50 so as to permit overlapping without disturbing the planes of the two bars and at the same time permit of the necessary relative adjustment between the two bars when obtaining the original line-up. After the film or negative has been registered and the film frame locked in registered position, the bars D and E will be removed and the negative holder assembly is then ready for attachment to the photographic printing machine proper.

Referring to the modification shown in Figures 7 and 8, the main base plate of the holder is indicated at 111 and has secured thereto in fixed position, a block 137, it being understood that there are four such blocks similar to the

blocks 37. Each block 137 is preferably provided with a pair of dowel holes 140—140 which receive corresponding dowel pins 141—141, on the underside of the cradle 70, the latter having upstanding flanges 71—71 at each end, which receive threaded adjusting screws 72—72. Adjustably mounted on the cradle 70 is a frame 73 which carries the end of the corresponding line-up bar D or E. By adjusting the screws 72, it is evident that the gauge edge of the bars D and E may be accurately positioned with reference to the holder A to coincide with the travel lines as above described and, when the proper position has been obtained, the block 73 is locked to the cradle 70, as by the screw 74. The bars D are hence removable by detaching the assembly comprising the bar D, block 73 and cradle 70, and may be accurately replaced by means of the dowel and dowel hole arrangement described.

In the modification shown in Figure 9, the line-up bars are formed of glass, as indicated at 75 and in this instance, instead of using an edge of the bar for registering, the glass bar is preferably provided on its underside with a longitudinal gauge line 76 and the reading effected by looking through the bar and bringing the register marks 44 into register with the line 76. To minimize the danger of breakage of the glass bars the latter may be bound with metal binding strips 77, as shown in Figure 9.

I have herein shown and described what I now consider the preferred manner of carrying out my invention, but the same is by way of illustration and not by way of limitation. All changes and modifications are contemplated that come within the scope of the claims appended hereto.

I claim:

1. In a device of the character described, the combination with a portable negative main holder having means thereon cooperable with corresponding means on a photographic printing machine adapting the holder to be attached to said machine in predetermined position with reference to the two travel lines of said machine; of register means on said holder definitely and predeterminedly coordinated with said two travel lines of said machine whereby a negative may be registered with respect to said means on said holder, said means comprising two separate bars detachably mounted on the holder, said bars extending at right angles to each other and having gauge lines intersecting at the center of the holder.

2. In a device of the character described, the combination with a holder having means thereon cooperable with corresponding means on a photographic printing machine adapting the holder to be attached to said machine in predetermined position with reference to the two travel lines of said machine; of separate line-up bars mounted on said holder; and means for adjusting the points of attachment of the ends of each of said bars with respect to the holder whereby to independently register the gauge portions of each of said bars accurately to correspond with the two travel lines of said machine.

3. In a register device of the character described, the combination with a negative main holder adapted to be positioned on a photographic printing machine in a known position; of an auxiliary frame detachably supported on said holder; a flexible film frame detachably supported on said auxiliary frame, the film frame

having a series of clamping and stretching jaws for a flexible film; and register means on said holder positioned in close proximity to a film carried by said film frame.

5 4. In a device of the character described, the combination with a negative holder having means thereon cooperable with corresponding means on a photographic printing machine adapting the holder to be retained in a predetermined position and location with respect to the two travel lines of the photographic printing machine; of a negative frame adapted to hold a negative thereon; removable register means definitely co-related to said two travel

15

lines of the machine, adapted to be supported by said holder and disposed in proximity to the negative whereby, upon adjustment of the negative frame with its negative as an entirety, relative to the holder, the negative may be registered with respect to the holder; adjustable means for maintaining the relative registered position of the negative frame with respect to the holder; and additional means for securing the negative frame to the holder in adjusted position whereby accidental displacement of the frame from the holder is prevented while the holder is being handled.
